UNITED STATES PATENT OFFICE.

JOHN J. KENNEDY AND CHARLES W. DAKE, OF CHICAGO, ILLINOIS, ASSIGNEES TO THE PYLE-NATIONAL COMPANY, OF CHICAGO, ILLINOIS, A CORPORATION OF NEW JERSEY.

CAB SWITCH.

Original application filed December 20, 1923, Serial No. 681,789. Divided and this application filed November 10, 1924. Serial No. 748,886.

Our invention relates to improvements in a cab switch and dimmer or compensation switch for locomotive electric headlights. It has for one object to provide a new and improved form of switch whereby the engineer may control the electric headlight. Another object is to provide a switch wherein the headlight may be turned on or off or dimmed dependent upon the driving conditions. Another object is to provide a durable, compact and convenient switch which will retain proper adjustment at all times. Other objects will appear from time to time throughout the specification.

Our invention is illustrated more or less diagrammatically in the accompanying drawings, wherein:

Figure 1 is a plan view;

Figure 2 is an elevation looking in the direction of the arrow in Figure 1;

Figure 3 is a bottom plan view;

Figure 4 is a wiring diagram.

Like parts are indicated by like characters throughout the specification and drawings.

A is an insulating base of hard rubber, bakelite, or similar material adapted to be mounted at any suitable point in the cab. A¹, A² are conductors leading to the lamp and to the source of power and in series with the lamp and power source. A³ is a pivot for the switch arm. It is electrically connected by means of a conductor bar A⁴ and binding post A⁵ with the conductor A¹.

A⁶ is the switch arm mounted on the pivot A³ having an insulated handle A⁷. The switch arm may be itself a conductor or it may, as indicated, have a conducting element A⁸ on its underside communicating with the pivot A³ and extending down-

wardly toward the handle A⁷. A⁹ is a quadrant mounted on the base A and in slidable engagement with the upper side of the handle A⁶. This quadrant may or may not be of insulating material. The quadrant is marked as indicated with the words "Off," "Dim," and "On" as indicating the operation of the switch in its various positions in relation to the operator.

B is a resistance coil or dimmer comprising a supporting base containing resistance

wire, the particular arrangement of the wire forming no part of the invention. Suffice it to say that the resistance is sufficient to dim the light as desired. B¹ is a binding post for the conductor A². This binding post extends down through the base A and communicates with the Y-shaped flat conductor bar B² recessed in the bottom of the panel A. One arm of this conductor bar communicates with one terminal of the resistance element as at B³, the other arm communicates with the contact segment B⁴ by means of a conducting screw B⁵ which passes up through the body of the panel. This conductor segment B⁴ is mounted on the panel A, and notched as at B⁴⁰ so as to make a yielding spring engagement with the arm A⁶ and to hold it in the "on" position against vibration. B⁶ is a dimmer contact segment mounted on the face of the base A, notched as at B⁷ to yieldingly hold the switch arm A⁶ in the "dim" position. This segment overlaps the segment B⁴ so that as the switch arm is moved to the right, it comes in contact with the "on" segment B⁴ before it disengages from the dimmer segment B⁶ so as to prevent surging in the circuit. The segment B⁶ communicates by means of a screw B⁷ with the conductor bar B⁸ recessed in the bottom of the panel A, which bar in turn communicates with a screw B⁹ and the opposed terminal of the resistance element B.

With the parts in the position shown in Figures 1, 2 and 3, the light is dimmed, the current passes from the conductor A¹ through binding post A⁵, conductor A⁴, switch arm A⁶, shoe A⁸, segment B⁶, screw B⁷, conductor B⁸, screw B⁹, through the dimmer resistance coil B, screw B⁸, conductor B², binding post B¹ to the conductor A² and the current for the light is then in circuit through the dimmer and a dim light is shown.

As the switch arm is moved to the right it first disengages from the spring held notched in the segment B⁶ and travels along the segment, the light being still dim until the shoe A⁸ engages the segment B⁴. At this time the dimmer is in parallel and short

circuited, the path of the current being as above indicated through the dimmer and also from the conductor A^1 , through binding post A^5 , conductor A^4 , screw A^3 , arm A^6 , shoe A^8 , segment B^4 , screw B^5 , conductor B^2 , binding post B^1 and to the conductor A^2 . Further movement of the switch lever to the right will cause the shoe A^8 to engage the notch B^5 and will break the circuit through the resistance element. The engagement of the shoe with the notch holds the switch in the "on" position and current will continue to pass directly through the lamp without passing through the resistance element.

C is a dead terminal segment on the face of the panel A . It is notched at C^1 to provide yielding means for holding the lever arm in the "off" position and prevent its dropping down under vibration. All the segments project upwardly from the face of the panel A and yieldingly force the switch arm up against the quadrant A^9 and being notched provide spring locking elements to prevent vibration or jarring or dropping of the switch arm from one position to another except when actually operated by the engineer.

The shoe A^8 may or may not be a spring. If it is a spring, it will serve the same function as the spring contact segments B^4 , B^6 and C and under some conditions they need not be springs. In other words, as long as there is a spring engagement between the switch arm and the contact segments, which spring engagement holds the arm against the quadrant and holds part of the arm against the segments and locks the parts together when the arm is in line with the notches in the segment, there is sufficient, and one or the other or both the segments or the shoe on the arm may serve as a spring.

Experience shows that it is frequently difficult in actual practice to maintain constant voltage regulation of a locomotive headlight generator and it sometimes happens that when a headlight is off, the generator speeds up and the voltage will rise as much as five or six volts. If the switch is suddenly closed and the over voltage thrown onto the lamp, and the lamp will ultimately burn out and therefore, it is desirable, especially since a dimmer is necessary anyway in lighting the light after it has been off to first throw a dimmer resistance into the circuit so as to load the generator, reduce the speed, and bring the voltage down to normal, the resistance holding the voltage down until normal speed has been reached, thus breaking the light. Our switch is peculiarly well adapted to perform this function because when the switch is moved from the "off" position toward the "on" position, the resistance is cut and the light burns dim for an appreciable length of time while the operator is moving the

lever across. As the lever or switch arm moves on, a time is soon reached when, without interrupting the dimmer resistance, there is a direct connection short circuiting the dimmer directly through the light, thus 70 protecting the light against such over voltage and avoiding surging in the circuit.

D is a motor generator set preferably mounted on a locomotive boiler and containing within the housing any suitable type of 75 steam governor. D^1 is a steam line by which boiler steam is fed to the generator set. D^2 is a conductor leading from the generator set to the incandescent motor headlight D^3 . The conductor A^2 leads from the binding 80 post B^1 on the switch to the metal conductor A^1 from the binding post A^5 on the switch to the motor generator set.

It will be evident that while we have shown an operative device, still many 85 changes might be made in the size, shape and arrangement of parts without departing materially from the spirit of our invention and we wish, therefore, that our drawings be regarded as in a sense diagrammatic. 90

This application is a division of my co-pending application Serial Number 681,789, filed December 20, 1923.

We claim:

1. A switch for locomotive headlights 95 comprising a panel, a switch arm pivoted thereon, a guide quadrant therefor and a plurality of contact segments adapted to yieldingly engage the arm as it is forced upwardly against the quadrant and held in 100 position, a resistance element, a plurality of binding posts, one of them connected to the switch arm, the other connected to one of the contact segments and to one end of the resistance element, electric connection 105 between the other contact segment and the opposed end of the resistance element, said live contact segments overlapping to permit simultaneous engagement with the switch arm.

2. A switch for locomotive headlights comprising a panel, a switch arm pivoted thereon, a guide quadrant therefor and a plurality of contact segments adapted to yieldingly engage the arm as it is forced upwardly against the quadrant and held in 115 position, a resistance element, a plurality of binding posts, one of them connected to the switch arm, the other connected to one of the contact segments and to one end of the resistance element, electric connection between the other contact segment and the opposed end of the resistance element, said live 120 contact segments overlapping to permit simultaneous engagement with the switch arm, each of said segments being notched at a point removed from the position of simultaneous engagement with the switch arm.

3. A control switch for locomotive headlights comprising a resistance element, a 130

switch arm and contact segments, one of them connected to the resistance element, the other connected directly to the circuit, the segments overlapping to permit simultaneous engagement with the switch arm.

4. A switch for locomotive headlights comprising an insulating panel, a switch arm pivoted thereon, a guide quadrant adapted to be engaged on its under side by the switch arm and a plurality of spring contact segments engaging the under side of the arm and yieldingly holding it against the quadrant, a resistance element mounted on the panel above the switch arm, and a plurality of binding posts on the panel, a conductor joining one of them and the pivot point of the switch arm, a conductor recessed in the bottom of the panel and joining the other binding post and one end of the resistance element and one of the segments, a conductor recessed in the under side of the panel joining the other end of the resistance element and one of the segments.

5. A switch for locomotive headlights comprising an insulating panel, a switch arm pivoted thereon, a guide quadrant adapted to be engaged on its under side by the switch arm and a plurality of spring contact segments engaging the under side of the arm and yieldingly holding it against the quadrant, a resistance element mounted on the panel above the switch arm, and a plurality of binding posts on the panel, a conductor joining one of them and the pivot point of the switch arm, a conductor joining the other binding post and one end of the resistance element and one of the segments, a conductor joining the other end of the resistance element and one of the segments.

Signed at Chicago, county of Cook and State of Illinois, this 16th day of April 1926.

JOHN J. KENNEDY.
CHARLES W. DAKE.
